RADIO RECEIVING APPARATUS

Application filed June 25, 1930. Serial No. 463,609.

This invention relates to new and useful improvements in a radio receiving apparatus.

The invention has for an object the provision of a device of the class mentioned which is of simple durable construction, dependable in use and efficient in action, and which can be manufactured and sold at a reasonable cost.

The invention proposes a radio receiving system including a filament circuit and a plate circuit, a power circuit for connection with a source of direct or alternating current and connected with said filament and plate circuits and including in series a variable resistance and in parallel the primary of a transformer having its secondary connected with a rectifier connected with said plate circuit and a lead from the B minus of the radio receiving system to a point before said variable resistance, and a single pole double throw switch for making the circuit through said primary or through said lead, a high inductance electromagnet being connected in parallel in the power circuit for automatically operating said switch according to the passage of alternating or direct current in said power circuit.

The invention also proposes to connect the filaments or the heaters of the vacuum tubes of the radio receiving system in a combination series-multiple for a low consumption of filament.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:—

Fig. 1 is a schematic wiring diagram of a radio receiving apparatus constructed according to this invention.

Fig. 2 is a schematic wiring diagram of a pair of tubes connected as proposed.

Fig. 3 is a schematic wiring diagram of four tubes connected as proposed.

The radio receiving apparatus comprises a radio receiving system 10 including a filament

circuit 11 and a plate circuit 12, a power circuit 23 connected with a source of direct or alternating current and connected with said filament and plate circuits and including in series the variable resistance 13 and in parallel the primary 14 of a transformer 15 having a secondary 16 connected with a rectifier 17 connected with said plate circuit 12 and a lead 18 from the input of the filter 30 to a point 19 before said variable resistance 13, and a single pole double throw switch 20 for making the circuit through said primary 14 or through said lead 18, a high inductance electromagnet 21 being connected in parallel in the power circuit for automatically operating said switch according to the passage of alternating or direct current in said power circuit.

The radio receiving system 10 may be of any design and construction and as illustrated on the drawing may easily be recognized by persons skilled in the art. The particular set shown is that of one stage radio amplification, detector, and four stages of audio-amplification. In all, six tubes have been shown. The filaments of these tubes are connected in a combination series-multiple as may be seen from a close inspection.

For defining the combination series-multiple connection above referred to Figs. 2 and 3 have been illustrated. In Fig. 2 a pair of vacuum tubes are shown with their filaments connected in series with each other. In Fig. 3 one pair of vacuum tubes are shown connected with their filaments in series with each other and a second pair of tubes with their filaments connected in series with each other, and these two groups are connected in multiples with each other forming the combination series-multiple referred to. In Fig. 1 there are three groups of tubes connected in the combination series-multiple just referred to.

The resistance 13 comprises a fixed resistance 13^a and a plurality of taps 24 near its rear end. A single pole rotary type switch 25 is arranged for individually engaging contacts on the various taps for obtaining the adjustment of the resistance. The single pole double throw switch 20 comprises a mov-

100

able pole 26 engageable with a stationary contact 27 or a second stationary contact 28. The movable pole 26 is in the lead 18 which connects with the point 19 to the front of the resistance 13. The stationary contact 28 is also in the lead 18 for concluding this connection when the pole 26 connects therewith. The stationary contact 27 is connected in series with the primary 14 of the transformer so as to conclude the parallel connection of the primary upon engagement with the movable pole 26.

The high inductance electromagnet 21 is provided with a winding 28' connected in parallel with the power circuit 23 immediately to the rear of the resistance 13. The core of the electromagnet draws the movable pole 26 to close the circuit with contact 28 when a direct current flows in the power circuit and a spring 29 draws the pole 26 to close the circuit with the stationary contact 27 when an alternating current flows in the power circuit. The winding of the electromagnet is of high inductance so that an alternating current cannot flow therethrough.

A filter 30 is connected in the plate circuit to the B positive contacts. The secondary 16 of the transformer has a central tap connected with the B minus which is the return of the plate current and return to the filament circuit of the residual and alternating current present in the filtering system 30. When a direct current flows in the power circuit 23 the lead which connects with the resistance 13 as shown in Fig. 1 is the positive lead, while the other lead is the negative one. When the power circuit is plugged in a direct current source, the core of the electromagnet 21 is magnetized by the passage of the current through the winding 28 and the core attracts the movable pole 26 to close the circuit with the stationary pole 28 and cause the positive side of the direct current to flow to the filter 30 through the lead 18. The current will be filtered and applied to the plates of the vacuum tubes.

The tubes in the radio receiving apparatus are connected in a combination series-multiple, that is, the filament of one tube is connected in series with a second as before described. So the plate current does not feed back through any one of the filaments, the plate current return (or B minus) is connected at the mid point, that is, between two filaments or heaters as shown in Fig. 2. Then another group with the filament or heaters connected in series as shown in Fig. 2 and a balanced plate current return terminal for the B minus is connected in multiples with the first group forming a filament or heater combination series-multiple. There is no change in the filament power supply circuit 23 when the current supply is changed at the input as there is a different voltage between the alternating supply and the direct cur-

rent supply (about 10 volts) that different voltage being taken care of by adjusting the switch 25, that is, the variable resistance 13.

It should be noticed that the particular way used for connecting the heaters or filaments is due in that some tubes used may be of relatively low amperage consumption and the cathode (see Figs. 2 and 3) are connected to one side of the heaters. The cathode is the plate current return and therefore it is impossible to connect more than two tubes with the heaters in series without the plate current feeding back through at least one heater and creating a very undesirable hum in the loud speaker when plugging the radio apparatus receiver in the alternating supply. The reversal of the wiring in the heater leads in order to produce a common connection for the B minus and therefore cutting the amperage in two for the power supply by using the series connection.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A radio receiving apparatus, comprising a radio receiving system including a filament circuit and a plate circuit, a power circuit for connection with a source of direct or alternating current and connected with said filament and plate circuits and including in series a variable resistance and in parallel the primary of a transformer having its secondary connected with a rectifier connected with said plate circuit and a lead from the input of the filtering system to a point before said variable resistance, and a single pole double throw switch for making the circuit through said primary or through said lead, a high inductance electromagnet being connected in parallel in the power circuit for automatically operating said switch according to the passage of alternating or direct current in said power circuit.

2. A radio receiving apparatus, comprising a radio receiving system including a filament circuit and a plate circuit, a power circuit for connection with a source of direct or alternating current and connected with said filament and plate circuits and including in series a variable resistance and in parallel the primary of a transformer having its secondary connected with a rectifier connected with said plate circuit and a lead from the input of the filtering system to a point before said variable resistance, and a single pole double throw switch for making the circuit through said primary or through said lead, a high inductance electromagnet being connected in paral-

lel in the power circuit for automatically operating said switch according to the passage of alternating or direct current in said power circuit, said variable resistance comprising a fixed resistance having a plurality of taps connected with its rear end, and a manually operable switch for concluding the circuit through any one of the taps.

3. A radio receiving apparatus, comprising a radio receiving system including a filament circuit and a plate circuit, a power circuit for connection with a source of direct or alternating current and connected with said filament and plate circuits and including in series a variable resistance and in parallel the primary of a transformer having its secondary connected with a rectifier connected with said plate circuit and a lead from the input of the filtering system to a point before said variable resistance, and a single pole double throw switch for making the circuit through said primary or through said lead, a high inductance electromagnet being connected in parallel in the power circuit for automatically operating said switch according to the passage of alternating or direct current in said power circuit, said lead including a stationary contact and the said movable pole for concluding the circuit as called for.

4. A radio receiving apparatus, comprising a radio receiving system including a filament circuit and a plate circuit, a power circuit for connection with a source of direct or alternating current and connected with said filament and plate circuits and including in series a variable resistance and in parallel the primary of a transformer having its secondary connected with a rectifier connected with said plate circuit and a lead from the input of the filtering system to a point before said variable resistance, and a single pole double throw switch for making the circuit through said primary or through said lead, a high inductance electromagnet being connected in parallel in the power circuit for automatically operating said switch according to the passage of alternating or direct current in said power circuit, said high inductance electromagnet being connected in parallel with the power circuit immediately to the rear of said variable resistance.

5. A radio receiving apparatus, comprising a radio receiving system including a filament circuit and a plate circuit, a power circuit for connection with a source of direct or alternating current and connected with said filament and plate circuits and including in series a variable resistance and in parallel the primary of a transformer having its secondary connected with a rectifier connected with said plate circuit and a lead from the input of the filtering system to a point before said variable resistance, and a single pole double throw switch for making the circuit through said primary or through said lead, a

high inductance electromagnet being connected in parallel in the power circuit for automatically operating said switch according to the passage of alternating or direct current in said power circuit, said single pole double throw switch having a movable pole adapted for connection with one stationary contact for closing the circuit through said lead or with a secondary stationary contact for closing the circuit through said primary of the transformer.

In testimony whereof I have affixed my signature.

ALEXIS PONCEL.
